BENDING BRAKE.
FILED JULY 21, 1920.

2 SHEETS-SHEET 2

UNITED STATES PATENT OFFICE.

NIC KRUMP, OF CHICAGO, ILLINOIS.

BENDING BRAKE.

Application filed July 21, 1920. Serial No. 398,003.

To all whom it may concern:

Be it known that I, NIC KRUMP, a citizen of the United States, and a resident of Chicago; in the county of Cook and State of Illinois, have invented certain new and useful Improvements in Bending Brakes, of which the following, reference being had to the drawings accompanying and forming a part hereof, is a specification.

10 This invention relates to bending brakes by means of which sheet metal of considerable thickness is bent or folded.

Among the objects of the invention are to lessen the number of parts and the cost of 15 a bending brake having determined strength and rigidity; to obtain a brake of the kind named which is durable, not liable to get out of order or to become broken, and not liable to get out of adjustment; to obtain a brake 20 by means of which accurate work may be done when a number of duplicate bends are to be made, and a brake which is easily understood and operated by men skilled in the art of bending sheet and bar metal.

25 In the drawings referred to and illustrating the invention

Figure 1 is a front elevation of a bending brake;

Fig. 2 is an end elevation; and

30 Fig. 3 is a vertical section on line 3—3 of Fig. 1, viewed as indicated by arrows.

A reference character applied to designate a given part indicates said part throughout the several figures of the drawing, wherever 35 ever the same appears.

A, A¹ and B, B¹, represent the standards or legs of the brake, a, a represent diagonally extending braces, and b, b, base members. Said legs, braces and base members are rigidly secured together by rivets C, C.

The bed of the brake is supported by the frame formed by standards A, A¹, B, B¹, braces a, a, and base members b, b, and comprises the channel iron D, (consisting of web b, and parallel flanges d¹, d²) the channel iron E, (consisting of web e and parallel flanges e¹, e²) and end members D¹, D¹. End members D¹, D¹ are respectively provided with a flange D², on which the ends of web

50 d of channel iron D rests, and to which said web is rigidly secured by rivets D³, D³. Flange d¹ of channel iron D is rigidly secured to standard or leg B¹, by rivets d², d².

The web e of channel iron E is rigidly secured to standards A, A¹, and to flange d² of channel iron D, by rivets e³, e³. Flange e² of

channel iron E forms the lower jaw of the brake.

E¹, E¹ represent adjustable members which are mounted on heads D¹, adjusted by means of bolt E², and secured in adjusted position by bolts E³, E³.

The upper jaw of the brake comprises members F, G and H. Member F consists of channel iron having the central web f, and flanges f¹, f². The web f is provided with a curving bend, as at f³, Fig. 3, so that the flange f² is in a horizontal plane, the portion of web f adjacent thereto is in a vertical plane, and the flange f¹ is in a vertical plane, 70 with the portion of web f between said flange f¹ and said curved bend f³ in a horizontal plane. (See Fig. 3.)

The members G, G, respectively consist of a head provided with a horizontal rib or flange g and an inclined rib or flange g¹; and also provided with a fulcrum (G¹) which is extended into slot G² in adjustable member E¹ on head D¹ at each end of the brake.

The plate H and channel iron F are rigidly secured together by rivets h, h, said rivets extending through the curved portion or bend f³ of web f. Heads G, G, are secured to the ends of channel iron F by rivets g², g² which extend through said web f and 85 through the ribs g, g; and plate H is secured to ribs g¹, g¹ by rivets g³, g³ which extend therethrough and through said plate.

I represents a steel plate on the under side of the horizontal flange f² of channel iron F, and is arranged to be forced down on to the sheet or bar of metal which is to be bent or folded by the brake, to hold said sheet or bar firmly in place by means of lever J, eccentric j on pivot J¹ and link K. K¹ represents a pivot which is secured in head D¹, 90 and on which the lower end of link K is pivotally mounted. k represents a stop to limit the movement of lever J in its travel from the position in which it is illustrated 100 in Fig. 2 to the left as viewed.

The bending leaf or apron of the brake comprises the heads L, L which are fulcrumed on pivots L¹, L¹ said pins being rigidly secured in heads D¹, D¹ plate M which 105 is secured to heads L, L by rivets l, l and the steel plate N, which is curved as at n, and the edge thereof adjacent to said curve secured to the plate M by rivets m, m.

O, O represent sockets on the sides of 110 heads L, L, O¹, O¹ represent rods, and O², O², counter weights on said rods.

Attention is called to the fact that the lower edge of plate H is bevelled to fit closely to the upper side of flange f^2 of channel iron F, and that the rivets h , h , which rigidly secure said plate to web f of channel iron F, extend longitudinally on said plate adjacent to said bevelled edge. This construction is designed to give great rigidity to the edge I of flange f^2 , when a plate, sheet, or bar of metal (as X, Fig. 3) is bent thereover by the turning of the bending leaf on its fulcrums L^1 , L^1 from the position in which it is illustrated into a plane parallel to, or at an acute angle to, plate H.

15 And also the plate N, bent or curved as at n and rigidly secured to the plate M by rivets m , m which extend longitudinally along said plate M, N adjacent to the upper edges thereof, is designed to receive 20 the thrust which is received in the turning of the bending leaf as last above recited and the bending of a sheet or bar (as X) by said turning of said leaf.

The portion of plate N extends beyond 25 the reverse bend n resisting, along with plate M, edge thrust on said plate M, to maintain said edge straight, that is, in a plane at right angles to the sides of said plates.

30 I claim:—

1. In a bending brake, the combination of standards, heads and a bed, all rigidly secured together, and an upper jaw adjustably mounted on said bed, said upper jaw comprising a channel iron having a longitudinally extending curved bend in the central web thereof, to position a portion of said web and one of its flanges in horizontal planes and a portion of said web and its 35 remaining flange in vertical planes, in combination with a plate provided with a bevelled lower edge arranged to rest on the upper face of said horizontally positioned flange, the body of said plate positioned adjacent to the bend of said central web and rigidly secured thereto.

40 2. In a bending brake, the combination of standards, heads and a bed all rigidly secured together, an upper jaw adjustably

mounted on said bed, and a bending leaf 50 pivotally mounted thereon, said bending leaf comprising plates, one thereof provided with a reverse bend to position the portions adjacent to said bend in parallel planes, and said plates rigidly secured together by 55 rivets extending longitudinally of said plates.

3. In a bending brake, standards, heads and a bed, all rigidly secured together, said bed comprising channel irons, the central 60 web of one thereof positioned in a vertical plane and its flanges in horizontal planes, and the central web of the other in a horizontal plane and its flanges in vertical planes, said vertical web and the vertical 65 flange adjacent thereto rigidly secured together, in combination with an upper jaw comprising a channel iron having a longitudinally extending curved bend in the central web thereof to position a portion of 70 said web and one of its flanges in horizontal planes and a portion of said web and its remaining flange in vertical planes, and a plate provided with a bevelled lower edge arranged to rest on the upper face of said 75 horizontally positioned flange, the body of said plate positioned adjacent to the bend of said central web and rigidly secured thereto.

4. In a bending brake, standards 80 arranged to support a bed member, said bed member comprising heads in combination with channel irons rigidly secured together by rivets extending through the central web of one and one of the parallel flanges of the 85 other, and the ends of said channel irons rigidly secured to said standards, in combination with a bending leaf pivotally mounted on said heads, said bending leaf comprising plates, one thereof provided with a reverse 90 bend to position the portions thereof adjacent to said bend in parallel planes, and said plates rigidly secured together.

NIC KRUMP.
